UNITED STATES PATENT OFFICE

115,624

DESIGN FOR A CALENDAR STAND

Carlyle N. Montanye, Baltimore, Md.

Application May 4, 1939, Serial No. 84,802

Term of patent 7 years

To all whom it may concern:

Be it known that I, Carlyle N. Montanye, a citizen of the United States, residing at Baltimore, in the State of Maryland, have invented a new, original, and ornamental Design for Calendar Stands, of which the following is a specification, reference being had to the accompanying drawing, forming part thereof.

Figure 1 is a front elevation.

Figure 2 is an end or side elevation.

Figure 3 is a top plan view, of a calendar stand, showing my new design.

I claim:

The ornamental design for a calendar stand, as shown.

CARLYLE N. MONTANYE.
